UNITED STATES PATENT OFFICE.

JOHN ICELY WARMAN, OF CHICAGO, ILLINOIS.

MULTIPLE DRILL.

SPECIFICATION forming part of Letters Patent No. 592,943, dated November 2, 1897.

Application filed June 25, 1896. Serial No. 596,844. (No model.)

To all whom it may concern:

Be it known that I, JOHN ICELY WARMAN, of Chicago, in the county of Cook and State of Illinois, have invented certain new and useful Improvements in Multiple Drills; and I do hereby declare that the following is a full, clear, and exact description thereof, reference being had to the accompanying drawings, and to the letters of reference marked thereon, which form a part of this specification.

This invention relates to multiple drilling-machines of that class wherein a plurality of drill-carrying spindles positioned at the same or at different angles are caused to move radially in an outward direction from a common center and simultaneously perform the operation of drilling.

The invention is illustrated in connection with a circular rim to be drilled; but it will be manifest without additional drawings that the invention may be applied for the purpose of drilling holes in other work, square or other conformation and not necessarily circular, and also to the drilling of such holes at desired intervals from each other and whether the drilled holes be equidistant from a common center or not.

My invention, speaking in a general way, comprises a frame provided with a substantially horizontal table upon which the work is to be placed and means for securing the work thereon, the latter consisting of a plurality of chucks adapted to be simultaneously operated to move inwardly and thus center and secure the work. The frame is adapted to carry a pair of annular racks which respectively engage pinions upon the upper and lower sets of drill-carrying spindles, whereby the latter may be suitably and uniformly rotated, motion being communicated simultaneously to the two racks from a single driving-shaft. The ends of the drill-carrying spindles are arranged to bear against a centrally-placed movable wedge or cone, which at times is caused to move upwardly, and thus independently of the rotation of the drill-carrying spindles press the latter outwardly to their work. The feed cone or wedge is herein shown as being actuated from a foot-lever, there being a short link and universal-

joint connection between the end of the lever and the end of a sliding shaft which actuates said cone.

A machine embodying my invention further comprises the usual bearings and connecting parts, as well as means for adjusting to any desired angle the several drill-carrying spindles.

The invention consists in the novel devices and combination of devices herein disclosed, and it will be more readily understood by reference to the accompanying drawings and subjoined description thereof and by the claims appended hereto.

In said drawings, Figure 1 illustrates in plan view a machine embodying my invention. Fig. 2 illustrates a central vertical sectional view of the main operative parts of the machine, some of the parts being shown in elevation. Fig. 3 is an enlarged vertical sectional view of the main operative parts of the machine, the section being taken upon the line 3 3 of Fig. 2. Fig. 4 is also an enlarged view looking down upon the table and upon the lower rack, the section being taken on line 4 4 of Fig. 3. Fig. 5 is a vertical longitudinal sectional view showing the construction of one of the drill-carrying spindles and its adjustable bearing. Fig. 6 is a side elevation of the adjustable bearing for the other drill-carrying spindles. Fig. 7 is a rear end view of the latter. Fig. 8 is a bottom plan view of the same. Fig. 9 is a front end view of the sleeve on the drill-carrying spindle. Fig. 10 is a transverse sectional view of the drill-carrying spindle, showing the groove therein.

I will first refer to the machine-frame and means employed for positioning and holding the work thereon, the letter A representing the machine as a whole. Suitably supported upon standards or legs A' is a table a. To the under side of the table a is a bracket a', suitably secured by bolts a² or otherwise. A second bracket A² depends from the table a, to which it is secured by bolts a³ or otherwise. Each of the brackets a' A² carries horizontally-arranged journal-bearings a⁴ a⁵, respectively, for supporting the main driving-shaft A³, the inner end of said driving-shaft being provided

with a driving miter-wheel A⁴. Motion is communicated to the shaft A³ in a familiar manner from any suitable source of power.

It will be noticed that in the form of the invention illustrated herein the table a is circular in general contour and has two main levels or elevations a⁶ a⁷, separated by the vertical shoulder a⁸. The lower and inner table a⁶ carries the adjustable brackets for holding the drill-carrying spindles, while the outer or upper table a⁷ carries the chucks for holding the work. Beneath the section of the table a constituting the portion lettered a⁷ and at suitable intervals a plurality of projecting plates A⁴ are secured by means of bolts a⁹ or otherwise, said plates extending radially outward beyond the outer margin of the section a⁷ of the table a.

A ring B is positioned around the outer section of the table a and rests upon and is supported by plates A⁴. A handle B' or other suitably projecting part is secured to the ring B in any convenient manner, as by bolts b or otherwise, whereby the ring B may be moved bodily upon the several supporting-plates A⁴ and around the table a.

B² is one of a series of movable or sliding chucks provided on its inner or engaging face with a cut-away portion, as shown at b', of any convenient configuration adapted for the work to be held upon the table—in this instance the concavo-convex rim C of an ordinary bicycle-wheel. The chuck is of such length as to extend beyond the section a⁷ of the table a and outward over the ring B. Upon the section a⁷ of the table and at such points where it is desired to have a chuck located I provide a pair of guide-plates or strips b², which may be secured to the table a⁷ by bolts b³ or in any suitable manner, and which afford a guide b⁴ within which the chuck B² may move. The inner or guide faces of the guide-plates b² will be positioned parallel with a radius of the circle upon which the ring B is described, so as to cause the chuck B² to move in a radial line toward and from the center when it moves at all.

The outer end of the chuck B² is provided with a vertical aperture through which a bolt B³ is passed, the lower end of the said bolt being provided with an enlarged head b⁵ and the upper end being provided with a nut b⁶, the latter being suitably located in a recess in the upper face of the chuck B². The enlarged head b⁵ of the several bolts B³ are each positioned in an elongated slot B⁴, extending vertically through the ring B, one slot to each bolt. It will be noticed particularly by reference to Fig. 1 of the drawings that these elongated slots are not concentric with the ring B, but are eccentrically arranged, whereby it will be obvious that upon moving the ring in either direction around the table a⁷ and upon the supporting-plates A⁴ the sides b⁵ of the slots B⁴, engaging as they do the heads b⁵ of the bolts B³, have a cam movement and move the bolts B³ radially outward from or

toward the center of the machine. Inasmuch as said bolts are passed through chucks B² and the latter are so confined in the guides b⁴ as to have movement only in a radial direction, the chucks are thus moved in the desired direction with the bolts B³. Assuming the chucks, therefore, to be in the position illustrated in Fig. 1, clamping the work to be drilled, a movement of the handle B' toward the top of the figure or in the direction indicated by the arrow will simultaneously move all of the chucks outwardly and away from the work and thus enable the latter to be removed from the machine and a fresh piece of work placed thereon. It will be manifest of course that after the new work has been placed on the table a movement of the handle B' in the direction opposite to that indicated by the arrow in Fig. 1 will cause the several chucks to simultaneously move inward and thus center and clamp the work upon the table preparatory to the operation of drilling.

I will next describe the drill-carrying spindles and the adjustable brackets for holding the same, referring more particularly to Figs. 4 to 10, inclusive, of the drawings.

The section a⁶ of the table a is provided with a concentric T-shaped recess or groove (designated as a whole by the letter D) comprising an enlarged lower portion d and a narrower portion d', so arranged that the top walls of the larger portion d will constitute shoulders d². At a convenient place an opening or aperture d³ is made which extends through the lower wall of the recess d to the lower surface of the portion a⁶ of the table, the opening being at least as large in diameter as is the said portion d in width, whereby a convenient means is afforded for the insertion of a bolt D', having a head d⁴. After the bolt has been inserted through the aperture d³ until the shoulders on its head d⁴ engage the shoulders d² of the recess d it may then be moved longitudinally into any desired position in the slot D. As many of the bolts D' will be used as may be necessary for the purpose of securing the drill-carrying-spindle brackets E to the table a⁶.

The brackets E each consist of two parts, a base e and an upper or journal portion e', the latter being provided, preferably, with a pair of upwardly-extending arms e². The under surface of the base part e is flat, as shown in Fig. 8, and is provided with a transversely-arranged rib e³ of such width as to nicely fit within the upper portion d' of the slot or recess D, and thus prevent a longitudinal movement of the part C radially or transversely with respect to the part a⁶ of the table a. A vertically-arranged aperture e⁴ extends through the base part e and the rib e³, said aperture e⁴ being of a size sufficient to permit the bolt D' to be passed therethrough. The upper surface of the base part e of the bracket E is concave or curved longitudinally, as clearly shown in Figs. 5 and 6, and

it is provided with a rib or tongue e^5 , extending lengthwise of the base portion e , said rib or tongue being relatively wide, although not extending the full width of the base-plate e , as clearly seen in Fig. 7. The under surface 5 of the journal or upper portion of the surface e' is given a convex configuration corresponding with the upper surface of the base part e , whereby the two surfaces will perfectly register, a central longitudinal groove being cut in said under surface portion e , thus forming two projecting flanges e^6 , adapted to embrace the tongue or rib e^5 , that enters the groove between said flanges. An elongated 10 slot or aperture e^7 extends through said upper portion e' , as indicated, for the reception of the upper portion of the bolt D' , said bolt being secured in position by a lock-nut D^2 , which latter engages screw-threads upon said 15 bolt and is crowded against a washer d^5 on the part e' adjacent to the said slot. The slot e^7 extends on either side of the bolt D' for some considerable distance in a direction lengthwise of the bracket E . 20

It will be obvious that upon loosening the nut D^2 the upper portion e' of the bracket E may be adjusted with respect to the lower portion e and the nut D^2 again tightened, whereby the inclination or direction of the 25 drill-carrying spindle may be suitably adjusted. In this connection it may be stated that the bracket E shown in Fig. 6 is of the same construction as that shown in Fig. 5, although the lower portion e is considerably 30 smaller in size, it being more convenient to make these parts of different sizes where one set of brackets carries the lower drill-spindles and the other carries the upper drill-spindles. All the brackets may obviously be of the 35 same size, if desired.

Each bracket-arm e^8 is provided with any suitable journal-bearing arranged longitudinally of the bracket E , for the purpose of supporting a drill-carrying spindle F . These 40 spindles are provided at one end with any suitable style of drill-holding chuck f , in which the drills F' are removably secured. The chuck f acts as a shoulder to engage the face e^8 of the journal-arm e^8 and thus limit the 45 longitudinal movement of the drill-carrying spindles F in one direction. Obviously, any suitable collar or stop upon the spindle may be used for the purpose, if desired. Near its 50 other end the spindle F is provided with a groove or slot f^1 , that extends lengthwise of the spindle. Surrounding the spindle F is a suitable sleeve f^2 , having a longitudinal opening therethrough, f^3 , equal in diameter to that of the drill-carrying spindle F , and provided 55 with a feather or rib f^4 , projecting within said opening f^3 , adapted to fit within the groove f^1 of the spindle, whereby a longitudinal movement of the carrying-spindle F may be secured without obtaining rotary movement 60 of the sleeve f^2 . The sleeve f^2 is provided at one end with an annular flange f^5 , adapted to engage the face e^9 of the inner bracket-arm

e^2 , and it is provided at its other end with a reduced but exteriorly screw-threaded portion f^6 . The length of the sleeve f^2 is such 70 that when its flange f^5 engages the face e^9 of the bracket-arm the threaded portion f^6 extends beyond the other face e^{10} of the bracket-arm. A bevel driving-pinion G is positioned 75 partially upon the spindle F and partially upon the sleeve f^2 , it being secured to the latter by means of screw-threads upon the interior surface of a suitable recess engaging the screw-threads upon the portion f^6 of the sleeve which extends into said recess, as shown 80 in Fig. 5. One surface or edge g of the driving-pinion G is thus brought into contact with the face e^{10} of the bracket-arm e^2 . From this arrangement it will be manifest that upon rotating the driving-pinion G and the sleeve 85 f^2 rotary motion will be communicated to the drill-carrying spindle F by reason of the rib or feather f^4 of the sleeve engaging the recess f^1 of said spindle. It will also be obvious that the drill-carrying spindle F may 90 be moved toward its work and withdrawn therefrom—that is to say, that it may be given a longitudinal movement quite independent of its rotary motion.

I will now proceed to describe the mechanism for imparting rotary motion to the drill-carrying spindles. 95

The two arms of the bracket a' unite at their lower ends and support a vertically-arranged journal-bearing h , which supports a movable 100 feed-bar H . Surrounding the feed-bar H is a tubular or recessed shaft H' , which rests at its lower end upon the upper end of said journal-bearing h and at its upper end is provided with a circular driving-rack I , secured 105 thereto by means of arms i . The lower face of the driving-rack I is provided with teeth i' , adapted to engage one of the sets of driving-pinions G . Rotary motion is communicated to the shaft H' from the driving-shaft 110 A^3 by means of a bevel gear-wheel h , suitably secured, as by a key h^2 or otherwise, to the lower end of the shaft H' , the teeth of which bevel h engage the teeth of the driving miter-wheel A^4 . A bearing is afforded 115 for the shaft H' by a suitable aperture through the lower portion of the curved bracket-arms h^3 , which latter terminate at their upper ends in laterally-extending flanges h^4 , by which the bracket-arms h^3 are secured to the under 120 surface of the plate a^6 of the table by bolts h^5 , passing through apertures in the flanges h^4 and into screw-threaded recesses in the table, or otherwise. The arms h^3 , Fig. 3, are positioned at right angles to the arms of the 125 bracket a' , Fig. 1, whereby strength and rigidity to the structure as a whole are secured.

A second drill-driving rack I' , provided on its upper face with teeth i^2 , that engage one of the sets of drill-driving pinions G , is supported by bracket-arms i^3 from a short sleeve i^4 , which surrounds the shaft H' . To the lower end of this sleeve i^4 is secured a bevel gear-wheel h^6 , adapted to engage the driving 130

miter-wheel A⁴. It will be perfectly obvious that when rotary motion is communicated to the driving-shaft A³ from any suitable source of power the drill-spindles F and the drills carried thereby, will be suitably rotated through the medium of the gears A⁴ h' h⁶, the racks I I', and the several pinions G.

It will be understood that the clearance between the gears and racks will be sufficient to provide for the adjustment above described.

I will next describe the means employed for feeding the drills to their work. The mechanism employed for this purpose consists of a cone J, arranged to slide vertically upon the shaft H'. The inner end of each drill-carrying spindle F rests against this cone J, as indicated in Figs. 1 and 2, whereby it will be manifest that when the cone J is raised each of the spindles will be moved longitudinally outwardly—i. e., in a radial direction toward its work.

The mechanism for moving the cone J vertically to feed the spindles forward to their work is as follows: The shaft H' is provided with a central aperture or recess j and telescopes over the feed-bar H, so that the latter may be moved longitudinally therein. The upper end of the feed-bar H is provided with an outwardly-extending arm or finger j', adapted to pass through an elongated slot j², that extends through the wall of the shaft H' to the recess j. The under surface or edge of the hub j³ of the cone J rests upon or is engaged by this arm or finger j'. The shaft H' having no vertical movement, it follows that when the feed-bar H is reciprocated therein in one direction—that is to say, is moved upwardly—the finger j' will lift the cone J and the latter will freely slide upon the shaft H', and it will be manifest that when the feed-bar H is returned or moved in the opposite direction said cone J will return by gravity to its lowermost or normal position, as illustrated in Fig. 3.

Any suitable means may be employed for actuating the feed-bar H, but I prefer to use a foot-lever K, suitably pivoted at k and connected at its inner end with the feed-bar H by a link K', the link having any suitable universal-joint connection with the lower end of the said feed-shaft. Surrounding a reduced portion l of the bar H is a rotatable collar L, provided with outwardly-extending pins or trunnions l'. A bolt l² passes through the plate or washer l³ and enters the lower end of the reduced portion l of the bar H, and thus secures the collar L rotatably to the bar H. The upper end of the link K' is bifurcated, the two arms k being provided with suitable apertures for the reception of the trunnions l'. By this simple arrangement a universal-joint connection is formed. The lower end of the link K' is also bifurcated, its two arms k² straddling the inner end of the foot-lever K and being pivotally secured thereto by pivot-bolts k³.

A cap K² may be secured to the top of the

shaft H' by screw-threads or otherwise, as shown, and thus confine the bracket-arms i of the upper driving-rack I in the proper position.

In operation, the cone J being in its lowermost position and the chucks B² being in their outermost position, the work C is placed upon the table and the handle B' moved around in the proper direction to cause all of the chucks to simultaneously move inwardly and thus position and center the work. Pressure is then brought upon the foot-lever K, the cone J is thus raised, and the drill-carrying spindles are moved outwardly simultaneously to their work until the necessary drilling is accomplished, the shaft A³ rotating in the meanwhile. Upon releasing the pressure on the foot-lever K the cone J drops by gravity and the drill-carrying spindles F are moved inwardly by hand, so as to disengage the drills from their work. The chucks B² are then moved outwardly by turning the ring B in the desired direction, and the work C is then removed from the table, when it will be found that the desired number of apertures corresponding with the number of drills employed will have been made through the work and in the desired relation or angle to each other. The machine is simple, easily managed, not liable to get out of order, and requires little or no repairing. By its use work may be turned out with great rapidity, and particularly such work as the bored rings or tires of bicycle-wheels.

While I have herein illustrated a desirable form of machine for embodying my invention, it will be manifest that many changes may be made therein without departing from the essential principle thereof, all of which changes or modifications I desire to be included in the scope of my invention. Except, therefore, as they are made the subject of specific claims, I do not desire to be limited to the details of mechanism herein shown.

I claim as my invention—

1. A multiple drilling-machine comprising a frame, a plurality of movable chucks thereon, means for actuating the chucks to engage and center the work, a plurality of adjustable drill-carrying spindles mounted on said frame, means for actuating said spindles and means for moving the spindles toward the work comprising a cam engaging the free ends of the same.

2. A multiple drilling-machine comprising a frame, a plurality of movable chucks mounted thereon, means for actuating the said chucks to engage and center the work, a plurality of drill-carrying spindles mounted in adjustable brackets secured on said frame whereby the angle of the drill-carrying spindles may be adjusted as desired, means for actuating said drill-spindles and means for moving the same outwardly toward the work comprising a cam engaging the free ends thereof.

3. A multiple drilling-machine comprising

a horizontal table provided with movable work-holding chucks, means for simultaneously actuating the chucks to engage and center the work, a plurality of adjustable 5 drill-carrying spindles mounted on said table, carrying drills on their outer ends, means for actuating the drill-carrying spindles and means for simultaneously feeding the drills to their work comprising a cam engaging the 10 free ends of said spindles.

4. A multiple drilling-machine comprising a horizontal table provided with movable work-holding chucks, means for simultaneously actuating the chucks to engage and 15 center the work, a plurality of adjustable drill-spindles mounted on said table carrying drills on their outer ends, means for actuating the drill-carrying spindles and means for feeding the drills to their work comprising a vertically-movable cam engaging the inner ends 20 of the drill-carrying spindles.

5. A multiple drill comprising a substantially horizontal table provided with movable chucks, means for simultaneously actuating 25 the chucks to engage and center the work, a plurality of drill-carrying spindles, brackets for said spindles adjustably secured to the table whereby the drill-carrying spindles may be adjusted in a desired direction, means for 30 simultaneously actuating the drill-carrying spindles, and means for simultaneously feeding the drills outwardly to their work, comprising a vertically-movable cone engaging the inner ends of the drill-carrying spindles, 35 substantially as described.

6. A multiple drilling-machine having a table provided with a T slot or recess in its face and a plurality of drill-carrying-spindle brackets mounted on said table each consisting 40 of a base and a spindle-support provided with a bolt-aperture therethrough and means for securing said parts adjustably together and to the table comprising a bolt engaging said slot and passing through the bolt-aperture 45 of said bracket.

7. In a multiple drill, the combination with a table, of a compound drill-carrying-spindle bracket, the upper member of which is provided with bearings for the said spindles, an 50 elongated slot extending through said upper member, a bolt-aperture extending through the lower member, the adjacent faces of the two members being tongued and grooved and the one being convexed and the other concaved, and a bolt engaging the machine-table 55 extending through the said bolt-aperture and through the said elongated slot, a lock-nut on the free end of said bolt, and a head upon the other end of said bolt engaging the table, substantially as and for the purpose described.

8. In a multiple drill, the combination with the table of the machine, of a two-part drill-carrying bracket, a concentric or annular inverted-T slot in the table, a headed bolt engaging the said slot and extending through a suitable aperture in the bracket, a lock-nut on the free end of the said bolt, the under

side of the lower part of the bracket being provided with a transversely-arranged rib adapted to engage the narrow portion of the inverted-T slot, substantially as described. 70

9. A multiple drilling-machine comprising a horizontal frame, two sets of radially-arranged drill-carrying spindles mounted thereon, each provided with a pinion, the spindles 75 of each set rotating in different planes, means for rotating each set of spindles, and means engaging the inner ends of said spindles for simultaneously feeding said drills to their work. 80

10. A multiple drilling-machine comprising a horizontal frame, two sets of radially-arranged drill-carrying spindles mounted thereon, each provided with a pinion, the spindles of each set rotating in different planes, means for rotating each set of spindles, and a cam engaging the inner ends of 85 said spindles for simultaneously feeding said drills to their work.

11. A multiple drilling-machine comprising a horizontal frame, two sets of drill-carrying spindles mounted thereon, each provided with a pinion, the pinions of the respective sets rotating in different planes, a separate driving-wheel for each set of pinions, 95 means for actuating said wheels, and a cam engaging the inner ends of the spindles for feeding said drills to their work. 90

12. In a multiple drilling-machine comprising two sets of drill-carrying spindles each 100 provided with a pinion, the pinions of the respective sets rotating in different planes, upper and lower circular racks engaging said pinions, the upper rack being connected to a shaft, and the lower rack being connected to a 105 sleeve surrounding said shaft, means for imparting rotary motion both to said sleeve and said shaft, substantially as described.

13. In a multiple drill, the combination with a table provided with means for securing the work thereon, of drill-carrying brackets adjustably secured on said table arranged to present the drills to the work at different angles, two sets of drill-carrying spindles having their rear ends in different planes, 110 driving-pinions on each drill-carrying spindle, an upper and a lower circular rack adapted to engage the driving-pinions on said sets of spindles, the upper rack being secured to a suitable shaft provided with a miter-wheel, 115 the lower rack being secured to a suitable sleeve surrounding said shaft, and also provided with a miter-wheel, a power-shaft, and a driving-wheel thereon, engaging said miter-wheels, substantially as set forth. 120

14. A multiple drilling-machine comprising two sets of drill-carrying spindles each provided with a pinion, the pinions of the respective sets rotating in different planes, upper and lower circular racks engaging said 130 pinions, the upper rack being connected to a shaft, and the lower rack being connected to a sleeve surrounding said shaft, means for imparting rotary motion both to said sleeve

and said shaft, and means for simultaneously feeding the drills comprising a cone longitudinally movable upon said shaft and having its outer surface in sliding engagement 5 with the inner or free ends of the drill-carrying spindles, a central aperture in said shaft, an elongated slot extending through said shaft and communicating with said aperture, a pin or finger secured to said feed-bar passing through the slot in said shaft and engaging the lower side of said cone, and means for telescoping the feed-bar within the shaft as desired, whereby the cone may be moved along said shaft and the drills be fed to their 10 work, substantially as described.

15. An annular multiple drilling-machine comprising a horizontal frame, a plurality of work-holding chucks mounted thereon, means for simultaneously actuating said 20 chucks to engage and center the work, two sets of radially-arranged, drill-carrying spindles adjustably mounted on said frame each provided with a driving-pinion and each set arranged to act at a different angle, means

for rotating said spindles simultaneously and 25 means for simultaneously moving said spindles toward the work comprising a cam engaging the inner ends thereof.

16. An annular multiple drilling-machine comprising a horizontal frame, a plurality of 30 work-holding chucks mounted on said frame, means for simultaneously actuating said chucks to engage and center the work, two sets of radially-arranged drill-carrying spindles adjustably mounted on said frame each 35 provided with pinions, the pinions of each set rotating in different planes, driving-gears engaging each set of said pinions to rotate the same, and means for moving said pinions outwardly toward the work comprising a movable cam engaging the inner ends thereof.

In testimony that I claim the foregoing as my invention I affix my signature in presence of two witnesses.

JOHN ICELY WARMAN.
